SCREEN CONSTRUCTION

William D. Bayley, Springfield, Ohio

Application February 19, 1934, Serial No. 711,884

11 Claims. (Cl. 189—64)

This invention relates to window assemblies and more particularly to fixed and adjustable closures used in connection with detention and semi-detention windows.

5 An object of this invention is to provide a screen for a closure that is readily removable by those in authority but not so by unauthorized persons.

10 Another object of this invention is to provide a closure for the ventilating area that is frictionally held in adjusted position.

15 Another object of this invention is to provide a screen for a ventilating area in a detention window that is provided with detention bars removable with the screen.

20 Another object of this invention is to provide a screen and closure assembly for a detention window that is cheap, that is dependable, efficient and easily constructed with a minimum amount of labor.

25 Another object of this invention is to provide frictional means for holding the closure in adjusted position.

30 Another object of this invention is to provide increased protection to the more vulnerable area of the window assembly.

35 With the above primary and other incidental objects in view, as will more fully appear in the specification, the invention consists of the features of construction, the parts and combinations thereof, and the mode of operation, or their equivalents, as hereinafter described and set forth in the claims.

40 In the drawings, Fig. 1 discloses a fragmentary elevation of a detention window showing the ventilating area with a portion of the screen broken away. Fig. 2 is an enlarged sectional view taken on the line 2—2 of Fig. 1. Fig. 3 is an enlarged sectional view taken on the line 3—3 of Fig. 1. Fig. 4 is a sectional view taken on the line 4—4 of Fig. 3. Figs. 5 and 6 disclose detail views of the latch assembly. Fig. 7 is a sectional view taken substantially on the line 7—7 of Fig. 3. Fig. 8 discloses another modification of the closure assembly. Fig. 9 is an enlarged fragmentary sectional view taken on the line 9—9 of Fig. 8. Fig. 10 is another fragmentary sectional view taken on line 10—10 of Fig. 9. Fig. 11 is a fragmentary sectional view taken on the line 11—11 of Fig. 8. Fig. 12 is a view of the latch disclosed in Fig. 8. Fig. 13 is a fragmentary sectional view taken on the line 13—13 of Figs. 3 and 8. Fig. 14 is an enlarged sectional view taken near the latch disclosed in Fig. 12.

45 55 In penal institutions, insane asylums, hospitals, orphanages and the like it is oftentimes desirable to provide a window that is of a semi-detention nature which will deter the free movement of objects through the ventilating area and also the free escape of the inmates. In the present in-

vention this has been accomplished by the use of a screen that is hooked and locked in position with respect to the ventilating area, the screen carrying additional detention bars extending across the more vulnerable portion of the window which prevents the inmate from escaping in case the screen is torn or otherwise removed. In order to prevent the removal of the screen the screen frame is preferably padlocked.

5 10 It is also desirable to provide a closure for the ventilating area that may be frictionally held in adjusted position without the use of latches or other locking devices. This has been accomplished by providing a spring pressed member that frictionally prevents the easy and free movement of the closure but permits the adjustment thereof. When the closure is in closed position a latch that is cheap and efficient has been provided for locking the closure so as to prevent the same from blowing open.

15 20 Like reference numerals indicate like parts throughout the several figures of the drawings.

A plurality of transversely arranged munin bars 10 divide the window into a plurality of spaces some of which are glazed, leaving a group 25 of spaces 12 vacant for a ventilating area. The munin bars 10 preferably extend across the ventilating area.

25 30 As may best be seen by referring to Figs. 2, 3 and 8, a screen 14 carried by a frame 16 is arranged to extend over the ventilating area so as to prevent the unauthorized passing of objects through the ventilating area and so as to prevent or deter escape therethrough. In addition thereto the screen serves as a tell-tale in case attempts are made to cut the duo-functional munin bars, as these also function as detention bars. The screen frame 16 carries hooks 18 arranged in hooked relation with the munin bar 10 extending along one side of the ventilating area. 40 The opposite side of the screen frame 16 is carried by hook shaped members 20 suitably attached to the opposite munin bar 10. One or more of the detention bars 22 supported by the screen frame 16 is arranged in spaced relation 45 with the munin bar 10 and carries a screen retaining member 24 passing through an aperture 26. Member 24 has an aperture 28 which receives a padlock 30 which prevents unauthorized removal of the screen. The extra detention bars 22 extending across the more vulnerable area of the window assembly prevent or deter the escape of inmates through the ventilating area in case the screen 14 is torn from its frame 16. The screen frame 16 is aligned with the outer margins 55 of the munin bars 10 bounding the ventilating area so as to prevent a neat appearance.

50 55 The closure disclosed in Fig. 3 includes a pivotally mounted frame 32 carrying a window pane 34 and held in adjusted position by a link 36 60

having one end pivotally mounted to the closure frame at 38 and the other end connected to a sliding pivot assembly 40. The pivot assembly 40 includes a stud 41 terminating in a head 42, 5 as best seen in Figs. 4 and 7, that is seated in an aperture 58 in a resilient member 44 which is located in a slot 46 formed intermediate the channel shaped member 48 and the web of the muntin bar 10. Spring member 44 is deflected 10 so as to have one portion 50 edged against the web of the dentention bar 10 and another portion or a pair of spaced portions 52 urged or edged against the bottom of the channel shaped member 48, member 48 being provided with a suitable 15 slot 54 which permits the pivot 40 to slide vertically as the closure is opened and closed. Member 44 exerts sufficient pressure against the sides of the retaining member so as to frictionally hold the closure in any adjusted position. As may 20 best be seen by referring to the disclosure in Fig. 7, member 44 is provided with a pair of squirts or struck-out projections 56 adjacent the aperture 58 which increases the effective bearing surface between member 44 and the head 40. The squirts 56 may be formed by a suitable die provided therefor which causes the metal adjacent the aperture to be ejected from the plane as originally found.

A lock assembly has been provided for locking 30 the closure in closed position. This lock assembly includes the casing 60 provided with a cylindrical bore 62 in which is seated a latch 64 including a cylindrical shank 66 surrounded by a spring 68 having one end abutting the casing 35 60 and the other end abutting the collar 70. The spring 68 urges the latch upwardly as viewed in Fig. 3.

The shank 66 is provided with a slot 72 through 40 which passes a handle 74 which exerts a camming action upon the loop 78 of the shank 66 to cause the latch 64 to move downwardly as the free end of the handle 74 is moved downwardly as disclosed in Fig. 3. This handle 74 is provided with an eye for the reception of a hook or rod 45 that may be used in adjusting the closure from one position to the other.

The latch 64 engages a keeper 82 that is preferably stamped from a piece of sheet metal and 50 provided with a pair of ears 84 which are welded to member 86 carried by the muntin bar 10 and forming a portion of the outside frame for receiving the closure 32. The keeper 82 is beveled at 88, which beveled surface cooperates with the beveled surface of the latch to permit the closure 55 to be moved into closed position without manually retracting the latch 64.

The bottom of the closure as viewed in Fig. 3 is supported upon a sill 94 that is arranged in hooked relation with respect to the flange 96 60 of the muntin bar 10. The vertical muntin bar 10 passing through the center of the ventilating area as disclosed in Fig. 1 is undercut at 98 which permits the assembly of the closure in the field 65 or on the job without cutting away the sill to accommodate the detention bars or muntin bars extending across the ventilating area. This arrangement of the sill forms a water-tight union between the frame and the muntin bar 10.

In the modification disclosed in Fig. 8 and 70 detailed views disclosed in Figs. 9, 10, 11, and 12, the closure 32 is pivotally mounted on a pair of movable pivot assemblies 110 and 112. The pivot assembly 110 includes a cylindrical sleeve 114 75 provided with an internal shoulder 116 adjacent

one end which abuts a spring 118 engaging a shoulder 120 upon a guide member 122 which terminates in a channel shaped slide 124 seated over a suitable guide 126 carried by the stationary portion of the closure frame 128. Member 122 has a cylindrical extension 130 passing through the spring 118 and through the end of the cylindrical sleeve 114. This sleeve 114 is attached to the closure frame 132 by welding or in any other suitable manner. As the upper end of the closure 10 is moved outwardly or to the right, as viewed in Fig. 8, from the full line position to the dot-dash position, the pivot 112 of the closure also swings outwardly and the pivot assembly 110 moves upwardly, the channel extension 124 following the 15 guide 126. Link 160 having one end pivoted at 112 has the other end pivoted at 152 to support the closure 32. The pivot at 152 is fixed to member 128.

The closure is retained in closed position by a 20 lock that includes a cam shaped member 140 pivoted at 142 to a support 144 carried by a portion 146 of the closure frame 132. As the handle 148 integral with the cam 140 is rotated the cam shaped portion 140 engages the keeper 150 when 25 the window is in closed position so as to securely lock it. The keeper 150 may be made in the same manner as the keeper 82 and welded to the upper cross piece 152 of the frame for the closure.

The sill 154 of the closure frame is arranged 30 in hooked relation with the transverse muntin bar 10 and is provided with a bight 156 which cooperates with the flange 158 to make one closure contact and the flanged extremity 161 of member 154 forms the other contact with the closure 35 frame.

From the above description it will be apparent that there is thus provided a device of the character described possessing the particular features of advantage before enumerated as desirable, but 40 which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means 50 and construction herein disclosed comprise the preferred form of several modes of putting the invention into effect, and the invention is therefore claimed in any of its forms or modifications within the legitimate and valid scope of the appended 55 claims.

Having thus described my invention, I claim:

1. In a window structure having a plurality of transversely arranged muntin bars dividing the window into a plurality of spaces some of which 60 are glazed, leaving at least one group of spaces vacant for ventilating area across which the muntin bars extend as detention bars, said structure including a screen assembly for the ventilating area including a screen frame hooked in position on one side of the ventilating area, characterized by said screen frame including an interlocking member cooperating with a muntin bar extending across the ventilating area and means associated with said interlocking member 70 for preventing the unauthorized removal of the screen.

2. A window assembly including a plurality of transversely arranged T-shaped muntin bars dividing the window into a plurality of spaces some 75

of which are glazed, leaving a group of spaces vacant for ventilating area across which the bars extend as detention bars, a screen overlying the ventilating area arranged in interlocked relation with respect to the muntin bars, and a closure assembly for the ventilating area on the opposite side of the screen, said closure assembly including a frame having a sill provided with a lip overhanging the flange of the bottom T-bar, the vertical T-bars extending across the ventilating area being undercut adjacent the bottom T-bar to receive the lip, and a closure adjustably mounted in said frame.

3. A window assembly including a plurality of transversely arranged flanged duo-functional muntin and detention bars dividing the window into a plurality of spaces some of which are glazed, leaving a group of spaces vacant for ventilating area across which the bars extend as detention bars, and a closure assembly for the ventilating area having a frame provided with a flanged sill interlocked with the flange of the bottom muntin bar bounding the ventilating area, the vertical bars extending across the ventilating area being undercut whereby the flange of the sill may be interlocked after assembly of the transverse muntin bars.

4. In a detention window including a plurality of transversely arranged flanged muntin bars dividing the window into a plurality of spaces some of which are glazed leaving a group of spaces vacant for ventilating area across which vertical muntin bars extend as detention bars, the vertical bars extending across the ventilating area being arranged to clear the flange of the outside horizontal muntin bar extending across the ventilating area, and a closure for the ventilating area including a frame having a lip extending into said clearance and arranged in overlapping relation with respect to said flange of the outside bar.

5. In a detention window including a plurality of transversely arranged T-shaped muntin bars dividing the window into a plurality of spaces some of which are glazed leaving a group of spaces vacant for ventilating area across which the muntin bars extend as detention bars, the vertical bars extending across the ventilating area being arranged in spaced relation with respect to the upper flange of the muntin bar extending horizontally across the lower edge of the ventilating area, and a closure including a frame having a lip arranged in overlapping relation with respect to said flange, said lip extending continuously across the ventilating area.

6. In a detention window including a plurality of transversely arranged muntin bars dividing the window into a plurality of spaces some of which are glazed leaving a group of spaces vacant for ventilating area across which the muntin bars extend as detention bars, the muntin bar forming the base of the ventilating area being provided with an upwardly extending flange arranged in spaced relation with respect to the vertical muntin bars extending across the ventilating area, and a closure assembly for the ventilating area, said closure assembly including a lip overhanging said flange, said lip extending continuously across the entire width of the ventilating area.

7. A closure assembly for a window having a plurality of transversely arranged muntin bars dividing the window into a plurality of spaces some of which are glazed, leaving a group of spaces vacant for ventilating area across which the muntin bars extend as detention bars, said

closure assembly including a frame carried by the muntin bars bounding the ventilating area, an adjustable closure mounted in said frame, the transverse muntin bars extending across the ventilating area and the closure being arranged in a relatively offset relation with respect to each other, and means including a spring moving in a path parallel to one of the muntins bounding the ventilating area for frictionally holding the closure in adjusted position, characterized by the path of the spring being offset with respect to the muntin bars across the ventilating area so as to clear the same.

8. A closure assembly for a window having a plurality of transversely arranged muntin bars dividing the window into a plurality of spaces some of which are glazed, leaving a group of spaces vacant for ventilating area across which the muntin bars extend as detention bars, said closure assembly including a frame mounted adjacent to the muntin bars bounding the ventilating area, the frame and the muntin bars extending across the ventilating area being arranged in a relatively offset relation with respect to each other, a closure adjustably mounted in said frame, and friction means including a resilient member traveling in a path parallel to one of the muntin bars bounding the ventilating area for frictionally holding the closure in any adjusted position, the path of said friction means being offset with respect to the muntin bars extending across the ventilating area.

9. A window assembly including a plurality of transversely arranged muntin bars dividing the window into a plurality of spaces some of which are glazed, leaving a group of spaces vacant for ventilating area across which the muntin bars extend as detention bars, a closure assembly including a sill overhanging a portion of one of the muntin bars to provide a water-tight joint and provided with a triple flange, two of which form a fold, and an adjustable closure cooperating with the flanges to provide a water-tight union.

10. A detention window assembly having muntin bars dividing the window into a plurality of spaces, some of which are glazed leaving a group of spaces vacant across which the muntin bars extend as detention bars, and a closure pivotally mounted upon a slidable support traveling along a guide, said support being resiliently and frictionally held in any adjusted position, characterized by the path of said slidable support being offset with respect to the transversely arranged muntin bars extending across and bounding the ventilating area to permit the closure carried by the support to clear the bars extending across the ventilating area.

11. A detention window assembly having muntin bars dividing the window into a plurality of spaces, some of which are glazed leaving a group of spaces vacant across which the muntin bars extend as detention bars, and a closure assembly mounted adjacent the ventilating area, said closure assembly having a mounting including a link having one end pivoted to the closure and the other end pivoted to means having a vertical movement in a guide for said means including a channel, said means including a spring frictionally holding the pivot in any adjusted position characterized by the channel being offset from said muntin bars extending across the ventilating area as detention bars to permit said means to travel past said bars.

CERTIFICATE OF CORRECTION.

Patent No. 2,021,398.

November 19, 1935.

WILLIAM D. BAYLEY.

It is hereby certified that error appears in the printed specification of the above numbered patent requiring correction as follows: Page 1, second column, line 57, for "prevent" read present; page 2, first column, line 11, for "dentention" read detention; and that the said Letters Patent should be read with these corrections therein that the same may conform to the record of the case in the Patent Office.

Signed and sealed this 11th day of February, A. D. 1936.
